UNITED STATES PATENT OFFICE

2,489,005

SANDER DEVICE

Constantine C. Bourdunis, Chicago, Ill.

Application December 1, 1947, Serial No. 788,981

3 Claims. (Cl. 51—187)

1

This invention relates to improvements in sanders. More particularly it relates to improvements with respect to providing an improved clamping means for clamping sand paper in a sander.

My invention involves said improvements with respect to a sander having a roll of sand paper which is adapted to be unwound as needed.

My invention also includes improvements with respect to a sander of the type which employs only a single sheet of sand paper. More specifically, my invention includes a provision of a lever to clamp the sand paper tightly in the sander.

In the preferred form shown, I have provided a base plate having an upturned flange, to which the sand paper is adapted, to be clamped by means of a loop and a wedging lever.

My invention also includes improvements with respect to the provision of a shaft and means for holding and winding sand paper upon the shaft.

In the preferred form shown, I have provided a square shaft with a square sleeve, to which the sand paper is adapted to be secured. The shaft and sleeve may be wound or unwound, as desired, and then the shaft may be secured tightly in place in a simple manner by securing the same tightly in place to a bracket to prevent that shaft from further unwinding.

I have also a modified form for a sander employing a single sheet of sand paper. Means are provided for clamping the sand paper in place, including a bracket and screw means.

Another object of the invention has been in the provision of the foregoing in a manner which is simple to make and assemble, and relatively low in cost.

Other and further advantages of the invention will appear from the specifications and claims and from the accompanying drawing.

Figure 1 is a plan view of the preferred form of my invention.

Figure 2 is a vertical longitudinal section.

Figure 3 is a section on the line 3—3 of Figure 2.

Figure 4 is a sectional line 4—4 of Figure 2, showing the holding element or clamp or wedging means.

Figure 5 is a plan view of a modified form.

Figure 6 is a vertical longitudinal section of the same.

Figure 7 is a detail of the holding member of the modified form.

As shown in the form which I have selected to illustrate the principle of my invention, I have shown a sander 10 having a bracket 11, a handle 12, and a sander plate 13 having end flanges 14.

The bracket holding the handle may be secured to the plate by screws or rivets or other means.

The bracket 11 has an upper extending end flange 15, to which is secured by any suitable

2

means, a bracket 16 having protruding flanges 17 and 18.

These flanges are adapted to support a sand paper holding and winding element. This holding and winding element 19 is made generally in the form shown of two parts, to-wit, a square shaped shaft 20 which has threaded apertures 21 on each end.

Also the rearwardly extending flanges 17 and 18 are bored, and the shaft 20 is adapted to be held in place frictionally by the rearwardly extending flanges 17 and 18 by means of knurled screws 21.

The other part of the holding and winding element is comprised in the form shown of sheet metal, which is formed in a square shaped sleeve, to correspond to the form of the shaft, so as to fit snugly thereon in the preferred form.

This may be described as a paper securing element 22. This paper securing element has a pair of ends 23 and 24 adapted to receive one end of a roll of sand paper. The ends referred to are the narrow ends of the sheet metal in which the paper securing elements are formed. These ends are shaped to meet each other.

One end 25 of the sand paper is inserted between the ends 23 and 24 and secured thereto by means of rivets 26 or other suitable means.

In positioning the parts, the shaft 20 is inserted in the paper securing element 22 and then the screws 21 are threaded into the shaft to support the holding and winding means 19 in the bracket 16.

The opposite end 27 of the roll of sand paper 28 is then inserted in a securing loop 29, which has an outer side 30, narrow sides 31 and 32 and inner side 33 adjacent to the handle.

The loop with the sand paper is dropped over the flange 14. Pivotally secured, as at 34, to the loop by rivets, or otherwise, is a wedging or clamping lever 35, as is clearly shown, especially in Figures 4, 1 and 2.

The lever 35 has flange 36 with a curved handle, and a second flange 37, having a curved cut-away shaped portion 38. When the loop and sand paper are in place with respect to the flange 14, then the lever is pressed down.

The curved cutaway portion 38 will wedge against the flange 14 and clamp the flange 14 against the paper and the outer side 30 of the loop to tightly hold the sand paper in place.

From the sand paper securing device, consisting of the loop and the lever, the sand paper is laid along the bottom of the plate 13, and then turned upwardly on the outside of the other flange 14.

At the other flange 14 there is another securing loop and lever, similar to what already has been described, at the opposite flange 14, and it is not believed necessary to describe that again.

The arrangement of the two loops and the clamping levers are clearly shown in Figure 1. The paper is then clamped also at the opposite flange and is tightly held in place also at said flange, thus securely holding the sand paper in the sander.

In the modified form shown in Figures 5, 6, and 7, I have shown a handle 39, and a bracket 40 supporting the handle, similar to that shown in the first form. Also attached to the bracket, 10 as in the first form, is a base plate 41; which may be slightly curved, as shown in Figure 6.

The first form also is shown to be slightly curved, as in Figure 2. There is provided a bracket 42, having an outward flange 43, and a 15 pair of inward flanges 44. The bracket has a rear extending lug 45, having an aperture 46.

This bracket is adapted to slidably engage flange 40, and prevents the bracket from dropping off.

The sand paper 47 is adapted to have one end 48 turned under the bottom of flange 43. There is a threaded stud 49 secured to the base plate 41, and this stud extends through an aperture 50 and a bracket 42. A knurled nut is adapted to be secured down on the stud, and clamp the bottom of the flange 43 against the end of the sand paper.

On the opposite end of the sander there is provided a sand paper clamping element, as just described, including the bracket 42.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

I claim:

1. In a device of the kind described, a sander having upturned flanges and securing means for securing sand paper against movement on said sander, said securing means including rectangular loop members adapted to be disposed about said flanges, and wedges adapted to be swung into position in said loops against the inner surfaces of said flanges to clamp such sand paper to the outer surfaces of said flanges, through wedge pressure against said loops co-directional with such clamping action.

2. In a device of the kind described, a sander having end flanges and sand paper securing means for securing sand paper against movement thereon, said securing means including loop members adapted to be applied one each about said flanges with portions of such sand paper between said flanges and respective sides of said loops, and wedging means normally bearing against the other sides of said loops, and serving to clamp the sand paper between the said respective sides of said loops and said flanges.

3. In a device of the kind described, a sand paper mounting means including a handle and an elongated plate with an upturned sand paper mounting flange at each end, a pair of rectangular loops which serve to confine such sand paper to said flanges, and individual wedge elements hinged interiorly to said loops and serving to be swung between the respective flanges and a part of the respective loop and clamp such sand paper to said flanges.

CONSTANTINE C. BOURDUNIS.
